UNITED STATES PATENT OFFICE

93,519

DESIGN FOR A PARLOR GAME BOARD

John C. Raborn, El Paso, Tex.

Application June 16, 1934, Serial No. 52,199

Term of patent 14 years

To all whom it may concern:

Be it known that I, JOHN C. RABORN, a citizen of the United States, residing at El Paso, in the county of El Paso and State of Texas, have invented a new, original, and ornamental Design for a Parlor Game Board, of which the following is a specification, reference being had to the accompanying drawing, forming part thereof.

I claim:—

The ornamental design for a parlor game board as shown.

JOHN C. RABORN.
